UNITED STATES PATENT OFFICE.

AUGUST WIEDENFELD, OF BOCHUM, GERMANY.

MINER'S SAFETY-LAMP.

SPECIFICATION forming part of Letters Patent No. 768,497, dated August 23, 1904.

Application filed January 6, 1904. Serial No. 187,860. (No model.)

To all whom it may concern:

Be it known that I, AUGUST WIEDENFELD, a citizen of the German Empire, and a resident of Bochum, Westphalia, Germany, have invented certain new and useful Improvements in Miners' Safety-Lamps, of which the following is a specification.

My invention refers to a miner's safety-lamp in which the igniting device is shut off from the outside and where the burner-tube and the wick-tube are provided with slots forming a conduit from the place where the ignition is effected to the top of the burner where the wick comes out.

The objects of my invention are, first, to obviate certain disadvantages adhering to the ignition devices heretofore in use—viz., the production of a spray of sparks passing the wire-gauze apt to become a source of accidents and soiling the glass to the detriment of the illuminating value of the lamp; second, to reduce the probability of an undesired extinction of the flame.

My device is illustrated by the drawings herewith, in which—

Figure 1 is a view of my lamp, partly in elevation and partly in section. Fig. 2 is a ground plan of the said lamp; Fig. 3, a front view of the burner with the conduit aforementioned. Fig. 4 shows the position of the two slots composing the said conduit—namely, a slot in the burner-tube and another in the wick-tube—adapted to permit the ignition of the wick, while Figs. 5 and 6 illustrate the normal position of the said slots. Figs. 7 and 8 show an elastic ring employed in my lamp, and Fig. 9 the wick-tube with a pin or bolt secured thereto.

My safety-lamp consists of a vessel 10, to which is soldered a cover 11, with a brim forming an annular rib with a thread on the outside for the receipt of a screw-ring 12. This ring holds the vertical bars 13, which are on their top held together by a flat ring 14. In this last-mentioned ring are riveted the lower ends of the bars 15, carrying the top lid or cap of the lamp. This framing, composed as described, incloses a compartment 16, which contains an igniting-pan 17, and a rolled-up paper match 18 is set tight between

the aforesaid annular rib and covered by a cap 19 with a flat rim and a raised center 20, forming a hood the purpose of which will hereinafter appear. This cover carries a tubular glass cylinder. The said glass cylinder carries a wire-gauze 22, tightly pressed on through the aforesaid flat ring 14 and the hoops 23 and 24, the said hoop 23 being an annular step placed by its middle horizontal portion upon the top of the said cylinder 21, 60 the lower vertical portion embracing the brim of the cylinder and the upper portion receding somewhat, so as to fit into the orifice of the ring 14. The hoop 24 is elastic, and its shape is shown in reduced scale by 65 Figs. 7 and 8 of the aforementioned drawings.

The essential part of my device is the construction and arrangement of the burner 25 and the tube for the wick 26. In the said burner there is provided a slot 27, which commences at or near the top of the burner and terminates under the hood 20 in a round opening 28, assuming with the latter the form of a pan with a tail. The tube holding the wick has likewise a slot 29, which is equal in length 75 to the slot 27. To the side of the said tube 26 containing the wick there is soldered a vertical pin 31, provided with a notch 30, by which it takes hold of a flat piece 35, embracing the burner-tube 26, turnable in said piece 35. The 80 said pin 31 has a rectangular bend below the said burner-tube, assumes then the form of a quadrangular bolt 32, and settles in a small tube 33 in the bottom of the vessel, which small tube can be turned by means of a lever 85 34, secured to and below the bottom of the lamp vessel. When the said four-cornered bolt and small tube are turned round, the aforementioned flat piece 35 will have to follow this motion, which is, however, restrained 90 by the stops 37 and 38 in the said flat piece. The sparks produced in the igniting-pan 17 by means of the aforesaid match take the way indicated in Fig. 1 by an arrow, pass the opening 28, and touch the wick immersed with 95 benzene. The flame thus produced ascends through the slots, forming a conduit for the same, being in the position indicated by Figs. 2 and 4, and igniting the wick above, no matter how far the top of the burner may be placed 100

over the igniting-pellet. When the ignition has been effected, the conduit should be at once taken apart by separating the aforesaid slots and giving them the position shown by Figs. 5 and 6, which is done by turning the aforesaid lever 34. This is necessary to avoid a passing of the benzene-vapors into the hood 20 during the use of the lamp collecting under said hood and driving out the oxygen required for the 10 flame, which would have as a consequence the darkening of the latter and, moreover, be apt to cause small explosions and extinguish the flame altogether. The aforesaid piece 35 has, further, a threaded perforation 39, receiving 15 a threaded bolt 40, which is supported by a small tube 41 and can be turned by a button 42. This provides for the adjustment of the height of the burner and that of the flame.

The lamp may be provided with a magnetic 20 lock constructed by me to prevent its opening by unauthorized persons, as described and claimed in my Patent No. 749,123, dated January 5, 1904.

The aforesaid paper match 18 is supplied 25 with a turning-bolt provided with a worm 44, and at its lower end, which is outside below the bottom of the lamp vessel, with a handle for turning and unwinding the paper match. This paper match may be of any well-known 30 variety adapted to be ignited by friction, the matches being in the form of a continuous web, carrying the fulminate.

Having now described my invention, what I claim as new, and desire to protect by Letters 35 Patent, is—

1. In a miner's safety-lamp a burner containing a wick-tube, both the said burner and the tube being each provided with a slot, the two slots being adjustable so as to form a conduit 40 reaching to the top of the burner, an igniter, a compartment composed of the cover of the lamp vessel and a cap or hood covering said compartment and separating it from the outside, said compartment containing said igniter 45 and match in said compartment, substantially as set forth.

2. In a miner's safety-lamp the combination of a burner containing a wick-tube, both the said burner and tube being each provided with a slot reaching to the top of the burner, an igniter, a compartment composed of the cover of the lamp vessel and a cap or hood covering the said compartment and separating it from the outside, said compartment containing 50 said igniter, a match in said compartment, with a vertical pin quadrangled at its lower end and provided near its upper end with a notch a horizontal flat piece embracing the said wick-tube and engaging in the said notch 55 60 in the said pin, a small tube in the bottom of the lamp vessel in which the said quadrangled end of the said pin engages, and a lever outside of the bottom of the vessel by which the

said small tube, the said pin, the said flat piece and the said wick-tube, being all engaged 65 one in the other, can be turned substantially as described and for the purposes as hereinabove set forth.

3. In a miner's safety-lamp the combination of a burner containing a wick-tube, both the 70 said burner and tube being each provided with a slot reaching to the top of the burner, an igniter, and a compartment composed of the cover of the lamp vessel and a cap or hood covering the said compartment and separating it from the outside, said compartment containing said igniter, a match in said compartment, with a vertical pin, quadrangled at its lower end and provided near its upper end with a notch, a horizontal flat piece embracing the said wick-tube and engaging by the said 75 notch in the said pin, the said flat piece being provided with stops, a small tube in the bottom of the lamp vessel in which the said quadrangled end of the said pin engages, and a lever outside of the bottom of the vessel by 80 which the said small tube, the said pin, the said flat piece and the said wick-tube, being all engaged one in the other, can be turned as far as the said stops will allow, substantially as 85 described and for the purposes hereinabove set forth.

4. In a miner's safety-lamp the combination of a burner containing a wick-tube, both the 90 said lever and tube being each provided with a slot reaching to the top of the burner, an igniter, a compartment composed of the cover of the lamp vessel and a cap or hood covering the said compartment and separating it from the outside, with a vertical pin quadrangled at its lower end and provided near its upper end with a notch, a horizontal flat piece embracing the said wick-tube and engaging by the said notch in the said pin, the said flat piece being provided with stops, a small tube in the 95 bottom of the lamp vessel in which the said quadrangled end of the said pin engages, a lever outside of the bottom of the vessel by which the said small tube, the said pin, the said flat piece and the said wick-tube, being all engaged 100 one in the other, can be turned as far as the said stops will allow, substantially as 105 described and for the purposes hereinabove set forth.

In witness whereof I have hereunto signed 110 my name in the presence of two witnesses.

AUGUST WIEDENFELD.
